UNITED STATES PATENT OFFICE.

CYPRIEN CHABOT AND GEORGE REHFUSS, OF PHILADELPHIA, AND EDWARD BLACKFAN MOORE, OF WEST CHESTER, PENNSYLVANIA, ASSIGNORS TO SAID EDWARD BLACKFAN MOORE.

BUTTON-HOLE SEWING-MACHINE.

SPECIFICATION forming part of Letters Patent No. 439,109, dated October 28, 1890.

Application filed February 15, 1887. Serial No. 227,716. (No model.)

To all whom it may concern:

Be it known that we, CYPRIEN CHABOT and GEORGE REHFUSS, citizens of the United States, residing at the city of Philadelphia, State of Pennsylvania, and EDWARD BLACKFAN MOORE, a citizen of the United States, residing at West Chester, in the county of Chester and State of Pennsylvania, have invented certain new and useful Improvements in Button-Hole Sewing-Machines; and we do hereby declare the following to be a full, clear, and exact description of the invention, reference being had to the accompanying drawings, which form part of this specification.

Figure 1 is a plan of bed-plate of sewing-machine partly broken away with the feed-slide and clamp thereon. Fig. 2 is an inverted plan of under side of feed-plate partly broken away on scale enlarged from that of Fig. 1. Figs. 3 and 4 are perspectives of details pertaining to feed-slide. Fig. 5 is a perspective of feed-slides shown in dotted lines and mechanisms for operating the rotary disk of said slide. Fig. 6 is an inverted plan of under side of bed-piece of machine partly broken away, showing operative mechanism. Fig. 7 is a perspective of loop-destroying finger and its operating-lever. Fig. 8 is a vertical section of throat-plate, showing loop-destroying finger and its operating-lever. Fig. 9 gives a sectional view of the throat-plate, two needles, and loop-destroyer; Fig. 10, a cam on main shaft E, with side cam, lever, loop-destroying finger, and spring.

Certain parts of these improvements relate particularly to that class of machines in which a button-hole stitch is formed by the conjoint action of two needles—an upper needle and lower needle—and have for their object to provide a construction whereby the thread-loop of the upper needle will be kept from being drawn too tight around the lower needle, so that when withdrawn the loop will be sufficiently large to permit the lower needle to pass up without forcing the goods up from the level of the throat-plate, and also when the stitching of the button-hole is completed and the upper thread cut the action of withdrawing the goods causes the end of the thread

that is cut to pass down through the goods, thus destroying the loop and preventing the stitching from unraveling. There are other advantages resulting from this loop-destroying finger passing through the throat-plate, as its action is near the top of the throat-plate, and thus reduces the quantity of thread to be drawn up by the take-up to a minimum which is of the greatest importance in making a good button-hole.

Having reference to the drawings, L is a loop-destroying finger, which is intermittently moved transversely in an opening o o in the side of the throat-plate Z. Said loop-destroying finger is fitted to move lengthwise back and forth in the inclined opening o o in the throat-plate Z, and is connected at one end to lever M, which is fulcrumed at m on the under side of the bed-plate of the machine, and is connected to a spring N, which has one of its ends attached to said bed-piece. A cam P on main shaft F of the machine presses against a stud m' on lever M, and with the spring N communicates a vibrating motion to said lever and an intermittent reciprocating movement to the loop-destroying finger L. The movements of loop-destroying finger L relatively to those of the needles are such that when the upper needle is descending the loop-destroying finger is out or withdrawn; but as the two needles ascend the lower needle, which is curved, having passed through the thread-loop thrown out by the upper needle and passing on up over the top of the upper needle just as the point of the lower needle reaches the throat-plate the loop-destroying finger L is thrust forward between the two needles, intercepting the thread-loop of the upper needle and retaining it until after the upper needle has reached its highest elevation. When the point of the lower needle reaches the top of the throat-plate, it practically stops until the upper needle has passed above the foot-plate and preferably reached its highest elevation. This enables the operator to remove the fabric without interference with the needles when the machine is stopped. When the machine is again started, the lower needle moves up quickly and drops

sufficiently to throw out a thread-loop for the upper needle to pass through in its descent; but the moment the lower needle passes above the throat-plate in its upward passage the loop-
5 destroying finger is withdrawn, leaving a sufficiently large loop for the needle to continue its upward passage without forcing up the edge of the material that is being stitched. When the stitching of the button-hole is completed and
10 it is ready to be removed from beneath the holding-clamp, the thread of the upper needle is cut or broken near the fabric through which it has passed. The loop-destroying finger L being still in the loop of the thread beneath
15 the fabric as the latter is drawn away, the cut end of the thread is drawn down through the material, destroying the loop, and thus preventing the stitching from unraveling.

What we claim as our invention, and for
20 which we seek Letters Patent, is—

1. In combination, the stitch-forming and cloth-clamping mechanism of a button-hole sewing-machine, its throat-plate, the said stitch-forming mechanism comprising an upper needle a^3 and a lower needle a^4 , an intermittently-moving loop-destroying finger L, and means for causing the same to intercept the thread-loop of the upper needle a^3 and to retain the same until after the said needle has
25 passed above the throat-plate, substantially as shown and described.

2. The combination, with the stitch-forming mechanisms of a sewing-machine, said mechanisms embracing a straight upper needle a^3 , located above the bed-plate and adapted to pass through the fabric, and a curved lower needle a^4 , located beneath the bed-plate and
30

adapted to move over the edge of the fabric, but both conjointly operated above and beneath the bed-plate, and adapted to pass alternately through the loops thrown out by each, and a throat-plate Z, having in addition to the usual opening through which the needles are operated a slot or opening $o o$, located on the side and at an angle to the opening for the needles, of the loop-destroying finger L, and means for intermittently moving said finger in said slot or opening $o o$, and causing said finger L to intercept the thread carried by upper needle a^3 and hold it until needle a^3 has passed above the throat-plate, substantially as described.

3. The combination, with the stitch-forming mechanisms, the loop-destroying finger L, and the throat-plate Z, having the slot or opening $o o$, of the pivoted lever or rod M, to which is attached loop-destroying finger L, stud M', cam P, spring N, and by which several means or their equivalents loop-destroying finger L is intermittently moved forward and backward in opening $o o$ in throat-plate Z, and means which cause it to intercept the thread carried by needle a^3 and hold it until needle a^3 has passed above the throat-plate, substantially as described.

In testimony that we claim the foregoing we have hereunto set our hands this 12th day of February, 1887.

CYPRIEN CHABOT.

GEORGE REHFUSS.

EDWARD BLACKFAN MOORE.
